CLAIM

The ornamental design for a display screen with graphical user interface, as shown and described.

DESCRIPTION

FIG. 1 is a front view of a first embodiment of a display screen with graphical user interface, showing our new design;

FIG. 2 shows the design of FIG. 1 in the context of different broken lines;

FIG. 3 shows the design of FIG. 1 in the context of different broken lines;

FIG. 4 shows the design of FIG. 1 in the context of different broken lines;

FIG. 5 is a second embodiment thereof;

FIG. 6 shows the design of FIG. 5 in the context of different broken lines;

FIG. 7 shows the design of FIG. 5 in the context of different broken lines; and,

FIG. 8 shows the design of FIG. 5 in the context of different broken lines.

The broken lines showing the electronic device illustrate environmental structure. The broken lines showing portions of the display screen with graphical user interface illustrate portions of the article. No subject matter depicted in any of the aforementioned broken lines forms part of the claimed design.
